12 Claims. (Cl. 118—10)

My invention relates to a device for applying a smoothing substance to filamentous material such as a paraffin applicator for textile thread material.

For certain operations in the textile industry, such as weaving and knitting for example, it is necessary to make the thread smooth in order to obtain better running and sliding qualities. This is primarily accomplished by coating the thread with paraffin while it is rewound from spinning cops onto cross-spools or flask spools. Paraffin applicator devices have accordingly been made in which the thread is drawn between a bearing surface and a paraffin ring lying thereon. In order to avoid wearing out one side of the paraffin ring and forming flutes therein, the paraffin ring can either be placed in rotation positively by suitable means or can be rotated automatically by the thread itself due to its chord-like course with respect to the paraffin ring. Paraffin applicator devices of this type nevertheless have a disadvantage in that the thread must run through at least one clamping point at which a break can occur of its own accord due to slight variations in cross section of the thread. Furthermore, it has also been shown that there is a great tendency for the filaments and dust to cling together at the clamping point and form lumps. This accumulation of filaments either is drawn off by the thread and wound up on the spool or tends to bind the thread and break it.

A paraffin applicator device has also been known in which the thread is guided over the face of a rotatable paraffin ring without clamping points and is pressed against the ring by guides located outside the ring and lying together opposite the face of the ring. It has been found however that the application of paraffin in a device of this type is insufficient and uneven. The paraffin take-up of the thread is dependent on the angle of rise or run-up angle of the thread onto the paraffin ring, and therefore on the angle at which the thread guides are disposed opposite the faces of the paraffin ring. Due to the take-up of the paraffin by the threads, this angle becomes ever smaller and so does the paraffin applying efficiency accordingly. In the known devices the axial position of the paraffin ring is adjustable with the help of a set screw; nevertheless, in order to achieve the best possible uniform quality, continuous paraffin applying of the threads, the axial position of the paraffin ring must be adjusted again and again by hand after the slightest wearing of the paraffin ring.

It is accordingly an object of my invention to provide a device for applying a smoothing substance to textile thread material, such as a paraffin applicator, which avoids all of the foregoing disadvantages of applicators of a similar nature that have been previously known.

It is a further object of my invention to provide a smoothing substance applicator for textile thread material in which the applying effectiveness of the smoothing substance such as paraffin is greater than in known applicators, and uniform qualities are obtained.

To this end, and according to a feature of my invention, I provide a smoothing substance applicator in which the strand of filaments that is to be covered with the smoothing substance (that is, a single thread, a double thread or two or more twisted or braided threads) is led

2

over the face of a rotatable body formed of a smoothing substance like paraffin and is pressed against the body by means of guides that are located exterior to the body. The body is seated outside of the region scored by the 5 thread either entirely or partly in pressing engagement with a support that is either centrally or eccentrically connected to the guides. Due to this type of body mounting, the smoothing substance e.g. the paraffin coating efficiency is independent of the body which becomes smaller and smaller, since the feed rate of the body is contingent on the corresponding rate of consumption thereof. Consequently, the filament strands are effectively pressed against the paraffin body without requiring clamping members. A paraffin applicator constructed in accordance with my invention thus provides a constant application of paraffin to the filament strands by maintaining the filament strands pressed against the paraffin body without clamping devices, the paraffin application being independent of the size of the paraffin body or the feeding force i.e. to press the paraffin against the thread or against the support member.

According to another aspect of my invention, the rotation of the smoothing substance body can be effected by providing the paraffin body with a rectangular recess and by mounting the body upon a mandrel of similar cross section, which is for example rotatable by a geared motor. The smoothing substance body is pressed against the support member or the support member against the body by force storing means, for example mechanically with a spring or weight, hydraulically, pneumatically, magnetically and the like. In order to increase the smoothing substance e.g. paraffin applying efficiency, a paraffin body can be provided with a recess into which at least one additional guide for the filament strand projects. For regulation or adjusting the application of paraffin, the axial position of the guide relative to the support member and thereby relative to the face of the paraffin body is adjustable for example by a micrometer screw. It is particularly advantageous if the individual guides for the filament strands are separately adjustable. A greater number of possible variations in the paraffin applying effect can thereby be produced.

According to another aspect of my invention and in order to be able to replace the smoothing substance e.g. paraffin bodies that are nearly consumed, it is desirable for either the guide holder, preferably jointly with the support, or the paraffin body to be pivotably mounted. In order to make the supervision of the consumed paraffin body easier for the attendant personnel, there is additionally provided in accordance with yet another aspect of my invention, a signal device such as a signal lamp that is controllable with respect to an adjustable paraffin supply.

Other features which are considered as characteristic for the invention are set forth in the appended claims. The invention, however, both as to its construction and method of operation, together with additional objects and advantages thereof, will be best understood from the following description of specific embodiments when read in connection with the accompanying drawings, in which:

FIG. 1 is a side-elevational view of one embodiment of a smoothing substance applicator constructed in accordance with the invention and including a partly sectional view of FIG. 3 along the line I—I taken in the direction of the arrows;

FIG. 2 is a rear-elevational view, partly in section, along the line II—II, taken in the direction of the arrows;

FIG. 3 is a sectional view of the embodiment shown in FIG. 1 along the line III—III taken in the direction of the arrows;

FIG. 4 is a side-elevational view of a second embodiment of my invention; and

FIG. 5 is still another embodiment of the smoothing substance applicator constructed in accordance with my invention.

Referring to the drawings and first particularly to FIGS. 1 to 3, there is shown a thread F which is led over the surface of a cylindrical body 1 formed of smoothing substance e.g. paraffin which has a coaxial recess 2 of square cross section. The recess 2 of the paraffin body fits on a bolt 3 of rectangular cross section which is driven by a drive motor 4, the paraffin body being axially displaceable on the bolt 3. A spring 5 applied against an intermediate disc 5a forces the paraffin body in the direction of the thread i.e. vertically downward as viewed in FIG. 1. The axial position of the paraffin body face that is scored by the thread is fixed by the preferably slightly convex-shaped bearing or contact surface 6a of a support member 6.

The support member 6 has three end portions or appendices 7, 8 and 9, on which the guides 10, 11 and 12 are located and which are pressed back against the face of the paraffin body. The guides 10, 11 and 12 are formed with bevelled starting surfaces which permit automatic introduction of the thread into the thread guides. The supporting member 6 is pivotably mounted on a pin 13 and is biased by a leaf spring 14 which exerts pressure on a lever arm 15 that extends from the supporting member 6, so that the supporting member 6 abuts against a stop pin 16 which fixes its position. It is understood that my invention consists of a paraffin applicator which permits constant paraffining of the thread with a construction that does not require clamping positions of thread F on the faces of the paraffin body 1, and which is independent of the size of the paraffin body or the force for feeding, that is for pressing the paraffin against the thread or against the supporting member.

The replacement of the consumed or worn paraffin rolls can be effected in an especially simple manner since the supporting member 6 can be swung about the pin 13, and the consumed paraffin ring removed and replaced by a new one, the supporting member being then released so that it returns to its original operating position under the biasing force exerted by the spring 14.

In FIG. 4 those elements which are the same as the elements shown in the embodiment of FIGS. 1 to 3 are given the same reference numerals. In the embodiment shown in FIG. 4, the thread guides 10, 11 and 12 are located on one side of the center line M so that the thread is led eccentrically across the paraffin body. Because of the eccentric position of the thread guides, the formation of radial flutes or grooves in the paraffin body which can occur, for example, by sudden increase in the tension of the thread, is avoided. Furthermore, in the embodiment of FIG. 4, another means of pressing the paraffin against the support member 6 is shown, as well as a signalling device connected thereto that is controllable in relation to an adjustable paraffin supply. The arm 17a of a three-armed lever 17 is subjected to a force exerted by a tension spring 18 which causes the lever arm 17b to be biased and to press against the paraffin ring 1 in direction toward the supporting member. A preferably adjustable contact 19 is located opposite to an arm 17c of the three-armed lever 17 and is connected to one pole of an electric current source 20. The arm 17c of the three-armed lever 17 is connected with the second pole of the electric source across a signal device, such as a signal lamp 21 for example. As paraffin is removed from the ring 1 by the thread, the three-armed lever 17 turns clockwise (FIG. 4) so that both contacts 19 and 22 come closer together and finally engage one another and close. The signal lamp 21 then lights and the attendant personnel are then warned that the paraffin ring 1 is to be replaced.

FIG. 5 shows yet another embodiment of my invention in which a paraffin ring 1 is driven by a geared motor

4 and is biased by a spring 5 against the slightly convex bearing or contact surfaces of a counteracting support member 23. A holding device 29 is connected by a hinge 28 at the center of the counteracting supporting member 23, the holding device 29 being provided with a thread guide 24 in front of and behind the paraffin ring as viewed in FIG. 5. For the sake of clarity in this case a centrally located portion of the thread guide which projects into the recess of the paraffin ring 1, similar to the guide 11 shown in FIG. 3, is not shown in this figure. Its construction should nevertheless cause no difficulty in view of the disclosure of the embodiments provided by FIGS. 1 to 4. In the embodiment illustrated in FIG. 5 there is furthermore shown only one of the outer thread-guide portions 24, the other outer guide member being a mirror duplicate thereof. A tension spring 30 pulls the holding device or fixture and therewith the thread-guide portion 24 in direction toward the paraffin body 1. By means of a micrometer screw 25, the axial position of the guide 24 with respect to the holder or support member 23, and thereby with respect to the faces of the paraffin body 1, can be adjusted in order to vary the paraffin applying effectiveness. The introduction of the thread into the guide 24 can be facilitated by slightly lifting or swinging the holding device about the hinge 28. Both guide portions 24 may be arranged with separate holding devices 29, and each of the holding devices 29 which is swingable about the hinge 28 can be provided with a micrometer screw 25 in order to individually adjust the height of the thread guides 24 with respect to the paraffin ring 1. The geared motor 4 for rotating the paraffin body is secured to one arm of a double-armed lever 26 which is pivotable about a central pin 27 so as to be able to replace the paraffin ring 1. The geared motor 4 is held in operative position by a leaf spring 31 which is formed with a bend in which the other arm of the double-armed lever 26 is received and by means of which the position of the double-armed lever 26 and consequently the motor 4 and paraffin ring 1 are fixed.

My invention is not limited to the use of paraffin bodies only but rather any smoothing or burnishing means of corresponding similar characteristics may be used instead of paraffin. Furthermore, the paraffin body or the like can have various shapes. However if a cylindrical paraffin body having an axial recess is employed in the paraffin applicator, it is then advantageous when the guides are located in such a way that the thread is guided eccentrically across the paraffin body. The formation of radial flutes or grooves in the paraffin body caused for example by a sudden pressure rise in the thread is avoided.

Although my invention has been illustrated and described as a paraffin applicator for textile thread material, it is not intended to be limited to the details shown since various modifications and structural changes may be made without departing in any way from the spirit of the invention. Such adaptations should, and are intended to, be comprehended within the meaning and range of equivalents of the following claims.

I claim:

1. A device for applying a smoothing substance to the surface of a filament, such as a thread or the like, comprising a rotatable body formed of the smoothing substance and having a filament-engaging surface portion; support means in pressing engagement with said body only at a location other than on said filament-engaging surface portion; and guide means carried by said support means outside of said body, said guide means guiding a filament across said filament-engaging surface portion and stressing the filament at a location situated away from said surface portion so as to press the filament into yieldable engagement with said surface portion.

2. A device for applying a smoothing substance to the surface of a filament, such as a thread or the like, comprising a rotatable body formed of the smoothing substance and having a filament-engaging surface portion;

support means in pressing engagement with said body at a location other than on said filament-engaging surface portion; and guide means carried by said support means outside of said body and comprising a guide centrally disposed on said support means in line with the axis of rotation of said body, said guide means guiding a filament across said filament-engaging surface portion and pressing the filament into yieldable engagement with said surface portion.

3. A device for applying a smoothing substance to the surface of a filament, such as a thread or the like, comprising a rotatable body formed of the smoothing substance and having a filament-engaging surface portion; support means in pressing engagement with said body at a location other than on said filament-engaging surface portion; and guide means carried by said support means outside of said body and comprising a guide centrally disposed on said support means in line with the axis of rotation of said body and at least another guide eccentrically disposed on said support means and guidingly aligned with said centrally disposed guide, said guide means guiding a filament across said filament-engaging surface portion and pressing the filament into yieldable engagement with said surface portion.

4. A device for applying paraffin to the surface of a filament, such as a thread or the like, comprising a rotatable body formed of paraffin and having a filament-engaging surface portion; support means in pressing engagement with said body only at a location other than on said filament-engaging surface portion; and guide means carried by said support means outside of said body, said guide means guiding a filament across said filament-engaging surface portion and stressing the filament at a location situated away from said surface portion so as to press the filament into yieldable engagement with said surface portion.

5. A device for applying a smoothing substance to the surface of a filament, such as a thread or the like, comprising a rotatable body formed of the smoothing substance and having a filament-engaging surface portion, said body being provided with a central aperture; support means in pressing engagement with said body at a location other than on said filament-engaging surface portion; and guide means carried by said support means outside of said body and comprising a guide centrally disposed on said support means in line with the axis of rotation of said body and projecting into the central aperture of said body, said guide means guiding a filament across said filament-engaging surface portion and pressing the filament into yieldable engagement with said surface portion.

6. A device for applying a smoothing substance to the surface of a filament, such as a thread or the like, comprising a rotatable body formed of the smoothing substance and having a filament-engaging surface portion; support means in pressing engagement with said body at a location other than on said filament-engaging surface portion; and guide means carried by said support means outside of said body and comprising a guide centrally disposed on said support means in line with the axis of rotation of said body, and at least another guide eccentrically disposed on said support means and guidingly aligned with said centrally disposed guide, said guide means guiding a filament across said filament-engaging surface portion and pressing the filament into yieldable engagement with said surface portion, the axial position of said guides with respect to said support means being adjustable.

7. A device for applying a smoothing substance to the surface of a filament, such as a thread or the like, comprising a rotatable body formed of the smoothing substance and having a filament-engaging surface portion; support means in pressing engagement with said body at a location other than on said filament-engaging surface portion; and guide means carried by said support

means outside of said body and comprising a guide centrally disposed on said support means in line with the axis of rotation of said body and at least another guide eccentrically disposed on said support means and guidingly aligned with said centrally disposed guide, the axial positions of said guides with respect to said support means and to one another being individually adjustable, said guide means guiding a filament across said filament-engaging surface portion and pressing the filament into yieldable engagement with said surface portion.

8. A device for applying a smoothing substance to the surface of a filament, such as a thread or the like, comprising a rotatable body formed of the smoothing substance and having a filament-engaging surface portion, said body being provided with a coaxial recess; support means in pressing engagement with said body at a location other than on said filament-engaging surface portion; and guide means carried by said support means outside of said body and comprising a guide centrally disposed on said support means and projecting into the recess of said body off-center from the axis of rotation of said body and at least another guide eccentrically disposed on said support means and with respect to said body, said guides being aligned with each other for eccentrically guiding a filament across said filament-engaging surface portion and pressing the filament into yieldable engagement with said surface portion.

9. A device for applying a smoothing substance to the surface of a filament, such as a thread or the like, comprising a rotatable body formed of the smoothing substance and having a filament-engaging surface portion; a support member mounted in pressing engagement with said body only at a location other than at said filament-engaging surface portion; and a plurality of aligned guides carried by said support member outside of said body, said guides being pivotable together with said support member in a direction toward and away from said body, said guides guiding a filament across said filament-engaging surface portion and stressing the filament at locations situated away from said surface portion so as to press the filament into yieldable engagement with said surface portion.

10. A device for applying a smoothing substance to the surface of a filament, such as a thread or the like, comprising a rotatable body formed of the smoothing substance and having a filament-engaging surface portion; a support member mounted in pressing engagement with said body only at a location other than at said filament-engaging surface portion; a plurality of aligned guides carried by said support member outside of said body; and means for pivoting said body in a direction toward and away from said support member and said guides, said guides guiding a filament across said filament-engaging surface portion and stressing the filament at locations situated away from said surface portion so as to press the filament into yieldable engagement with said surface portion.

11. A device for applying a smoothing substance to the surface of a filament such as a thread or the like, comprising a support member; a rotatable body supported by said support member, said body being formed of the smoothing substance and having a filament-engaging surface portion; a plurality of aligned guides carried by said support member outside of said body; first biasing means for biasing said body toward said guides and into engagement with said support member at a location on said body other than at said filament-engaging surface portion; and second biasing means for biasing said guides toward said rotatable body and for pressing a filament guided by said guides into yieldable engagement with the filament-engaging surface portion of said body.

12. A device for applying a smoothing substance to the surface of a filament such as a thread or the like, comprising a rotatable body formed of the smoothing

substance and having a filament-engaging surface portion; support means in pressing engagement with said body only at a location other than on said filament-engaging surface portion; guide means carried by said support means outside of said body, said guide means guiding a filament across said filament-engaging surface portion and stressing the filament at a location situated away from said surface portion so as to press the filament into yieldable engagement with said surface portion so that the filament is coated with smoothing substance removed from said body; and signal means responsive to a predetermined reduction in size of said body as the smoothing substance is removed.
